Primary Examiner — Cynthia Ramirez*(74) Attorney, Agent, or Firm* — Ballard Spahr LLP**CLAIM**

The ornamental design for a pallet, as shown and described.

DESCRIPTION

FIG. 1 is a top perspective view of a pallet showing my new design;

FIG. 2 is a front devotional view thereof;

FIG. 3 is a rear elevational view thereof;

FIG. 4 is a right side plan view thereof;

FIG. 5 is a left side plan view thereof;

FIG. 6 is a top plan view thereof;

FIG. 7 is a bottom plan view thereof; and,

FIG. 8 is a cross-sectional view thereof, taken at line 8-8 of FIG. 7.

The dash-dot line in FIG. 7 shows the cross-sectional plane which FIG. 8 is taken and forms no part of the claimed design.
